UNITED STATES PATENT OFFICE.

CHARLES BENJAMIN REDRUP, OF CARDIFF, ENGLAND.

PISTON-ROD CONNECTION.

1,014,517.

Specification of Letters Patent.

Patented Jan. 9, 1912.

Application filed May 6, 1911. Serial No. 625,532.

To all whom it may concern:

Be it known that I, CHARLES BENJAMIN REDRUP, a subject of the King of England, residing at Canton, Cardiff, in the county of 5 Glamorgan, Wales, England, have invented certain new and useful Improvements in Piston-Rod Connections, of which the following is a specification.

This invention is particularly applicable 10 to plungers or pistons having connecting-rods of the non-cross-head type, such as are now used almost exclusively in internal combustion engines. Rods thus pivoted direct to the pistons or plungers without a cross-head 15 exert, as is well known, considerable side thrust upon the connecting-rod end of such pistons or plungers and it has been proposed to get over this difficulty by the use of ball bearings applied to the piston or various 20 parts movable with the piston.

According to this invention the anti-friction bearing for the piston takes the form of one or more rollers so situated that their axes are concentric with the point about 25 which the connecting-rod pivots. One or more such rollers may be mounted on the gudgeon-pin, the axes of the roller being concentric with the same. When carried by the gudgeon-pin the roller or rollers are conveniently mounted on the central portion so 30 that the ends may be free to engage the piston. When the rollers are carried by the gudgeon-pin they are approximately of the same diameter as the bore of the barrel or 35 cylinder in which they are employed.

In the accompanying drawings, Figure 1 shows in side elevation an anti-friction device constructed according to one method of carrying out this invention, the device being 40 mounted in a cylinder which is broken away for the sake of clearness; Fig. 2 shows the same anti-friction device in section on a plane coincident with the axis of the gudgeon-pin of the piston, Fig. 3 shows in section on a 45 plane coincident with the gudgeon-pin of the piston an anti-friction device constructed according to another method of carrying out this invention, and Fig. 4 shows the parts illustrated in Fig. 3 in perspective and 50 separated from each other, the piston being partly broken away for the sake of clearness.

Like letters indicate like parts throughout the accompanying drawings.

55 The cylinder A may be of any ordinary

construction, that shown being intended for an internal combustion engine, but if the apparatus was a pump, a pump-barrel would be substituted for this cylinder. The piston B, or in the case of a pump, the pump-plunger, has side ears B¹ which carry a gudgeon-pin B². On the gudgeon-pin a liner B³ may be mounted and at the center of the gudgeon-pin is mounted a roller C. The connecting-rod D is bifurcated at D¹ to engage the ends of the gudgeon-pin on opposite sides of the roller. The roller is approximately of the same diameter as the bore of the cylinder A, and the face C¹ of the roller, which is intended to bear against 60 the interior wall of the cylinder, is formed to part of a sphere, so that it may fit the cylinder, as will be readily understood.

It will be seen that the thrust of the connecting-rod D when in the position shown in 75 Fig. 1, would thrust the gudgeon-pin end of the piston against the right-hand side of the interior wall of the cylinder, but this thrust instead of being borne by the piston is now taken by the roller C, which rolling on the 80 surface of the cylinder offers much less resistance than would be afforded by a sliding body such as the piston.

In the construction shown in Figs. 3 and 4, the roller is divided into two parts, or 85 made in the form of two separate rollers E E' respectively, placed at opposite ends of the gudgeon-pin F. Each roller is made approximately hemispherical, but the rollers do not touch at the center, space being 90 left between them for the connecting-rod G and an arm H' that is carried by the piston H. The connecting-rod G has a head G' whereby it is engaged with the gudgeon-pin, and the arm H' of the piston is bifurcated 95 at H² and engages the gudgeon-pin on opposite sides of the head G'. The operation of this construction of roller is the same as with the roller C C'.

By using an anti-friction bearing such as 100 constitutes the subject matter of the present invention, the connecting-rod parts can be made shorter than is usual in practice without unduly increasing the friction due to side thrust. Usually the length of the connecting-rods employed in internal combustion engines equals the length of stroke multiplied by 2.5 whereas in an engine wherein the present invention is employed, the length of the connecting-rods can be reduced 105 110

so that they equal the stroke multiplied by 1.5 only, thereby rendering the whole engine more compact.

It will be understood that the two constructions described above, are only given by way of example and that modifications may be made in detail without departing from the spirit of the invention.

What I claim as my invention and desire 10 to secure by Letters Patent is:—

1. The combination with a cylinder of a piston therefor, a connecting rod pivotally secured to the piston, and a roller arranged beyond the contacting portion of the piston 15 with the cylinder for engaging the cylinder to prevent the thrust of the connecting rod on the piston, substantially as described.

2. The combination with a cylinder of a piston therefor, a connecting rod pivotally secured to the piston, and rotatable means 20 movable with the piston and arranged beyond the contacting portion of the piston with the cylinder for engaging the cylinder to take the thrust of the connecting rod, 25 substantially as described.

3. The combination with the cylinder of a piston therefor, ears projecting from one end of the piston, a connecting rod pivotally secured to the ears, and means revoluble

around said pivot point engaging the wall 30 of the cylinder for relieving the thrust of the connecting rod on the piston, substantially as described.

4. The combination with a cylinder of a piston therefor, ears projecting from one 35 end of the piston, a transverse pin carried by the ears, a connecting rod pivoted on the pin, and means rotatably mounted on the pin and engaging the wall of the cylinder 40 for relieving the thrust of the connecting rod on the piston, substantially as described.

5. The combination with a cylinder of a piston therefor, a transverse pin carried by the piston beyond its contacting portion 45 with the cylinder, a connecting rod pivoted on the pin, and hemispherical shaped members rotatably mounted on the ends of the pin and engaging the wall of the cylinder 50 for relieving the thrust of the connecting rod on the piston, substantially as described.

In testimony whereof I have signed my name to this specification in the presence of two subscribing witnesses.

CHARLES BENJAMIN REDRUP.
